O. MILETTE

WINDOW

Filed March 21, 1924

UNITED STATES PATENT OFFICE.

OCTAIVE MILETTE, OF MONTREAL, QUEBEC, CANADA.

WINDOW.

Application filed March 21, 1924, Serial No. 700,922, and in Canada January 21, 1924.

The present invention pertains to a novel window of the type embodying a pair of slidable sashes, the principal object of the invention being the provision of a device of this character in which the sashes are hinged as well as slidable.

This additional feature is particularly desirable in cleaning the windows as well as for ventilation purposes. In order to accomplish the purpose of the invention, the window frame is formed with the usual grooves for the sashes, and in a pair of these grooves are mounted slidable members. The sashes are hinged to these members, while the other side of the frame carries suitable devices for locking the free ends of the sashes in closed position when desired.

The invention is fully disclosed in the following description and in the accompanying drawings in which

Figure 1 is a front elevation of the window constructed in accordance with the invention;

Figure 2 is a section on the line 2—2 of Figure 1;

Figure 3 is a similar section showing the sashes swung on their hinges;

Figure 4 is a fragmentary elevation of the sash balancing device; and,

Figure 5 is a fragmentary perspective view of one of the hinges.

Reference will now be had to these views by means of like characters which are employed to designate corresponding parts throughout.

The numeral 1 indicates the sash frame of usual construction which contains a lower sash 2 and an upper sash 3. These members are slidably mounted in suitable grooves 4 and 5 in one side of the frame and similar grooves 6 and 7 in the opposite frame side. It will be observed that the grooves 6 and 7 are made by a retaining strip 8 attached to the frame side by means of a hinge 9.

The grooves 4 and 5 contain balancing weights 10 to which are attached cables 11, the latter passing over pulleys 12 mounted in the frame in the usual manner. The remaining ends of the pulleys are attached to the sashes as shown in detail in Figure 4.

The grooves are traversed by slidable strips 13 having their edges received in

notches 14 cut in the sides which limit the width of the grooves. Each of these members is formed intermediate its ends and at one edge thereof with a pair of ears 15, as shown in Figures 1, 2, 3 and 5. Each sash carries a pair of leaves 16 which, when connected to the corresponding ears, form hinges on which the sashes may be turned. Opposite the ears, the members 13 are formed with lugs 17 receivable in notches 17' cut in the sashes to insure a tight fit when the sashes are closed, as in Figure 2.

The frame side opposite that to which the sashes are hinged carries a hinged bead 18 terminating at the points 19 and 20. The ends of the bead are engaged by strips 21 and 21' fixedly secured to the frame. When the sashes are in the position shown in Figure 1, the upper member 3 is retained by the strip 21, while the bead 18 is locked against the lower member 2 by means of fastening devices 22. When the sashes are to be swung outwardly on their hinges, the bead 18 is released and the lower sash is raised to a position between the points 19 and 20 so that it can clear the fixed members 21 and 21'. After this sash has been swung outwardly, the strip 8 may be moved out of the path of the sash 3, whereby the latter also may be swung outwardly.

While a specific embodiment of the invention has been illustrated and described, it is to be understood that various alterations in the details of construction may be made without departing from the spirit of the invention as indicated by the appended claim.

Having thus fully described the invention, what I claim as new and desire to protect by Letters Patent is:—

A window comprising a frame having a pair of grooves in one side thereof and aligned notches in the walls of said grooves, slidable strips mounted in said grooves and projecting into said notches, an ear and a lug bent from the opposite edges of each strip, window sashes hinged to said ears, the hinged ends of said sashes having notches adapted to receive said lugs.

In witness whereof I have hereunto set my hand.

OCTAIVE MILETTE.
